(57) **CLAIM**

The ornamental design for a lightweight ball, as shown and described.

DESCRIPTION

FIG. 1 is a top, front-right perspective view of the lightweight ball, showing my new design.

FIG. 2 is a bottom, front-right perspective view of the lightweight ball.

FIG. 3 is a front elevation view of the lightweight ball.

FIG. 4 is a rear elevation view of the lightweight ball.

FIG. 5 is a top plan view of the lightweight ball.

FIG. 6 is a bottom plan view of the lightweight ball.

FIG. 7 is an exploded cross-sectional of the lightweight ball taken along section line 7-7 in FIG. 3; and,

FIG. 8 is an exploded cross-sectional view of the lightweight ball taken along section line 8-8 in FIG. 3.

The broken lines in the drawings illustrate portions of the lightweight ball that form no part of the claimed design.

1 Claim, 8 Drawing Sheets
